UNITED STATES PATENT OFFICE.

JOHN B. DOUGHERTY, OF ROCHESTER, NEW YORK.

IMPROVED HOOP-MACHINE.

Specification forming part of Letters Patent No. 40,613, dated November 17, 1863.

To all whom it may concern:

Be it known that I, JOHN B. DOUGHERTY, of the city of Rochester, county of Monroe, and State of New York, have made and invented a certain new and Improved Machine for Forming Sawed or Cut Splints into Barrel-Hoops; and I do hereby declare the following to be a full and accurate description of the same, reference being had to the accompanying drawings, making part of this specification, and to the letters of reference marked thereon, same letters referring to like parts in all the figures.

Of said drawings, Figure 1 is a plan of my improved machine. Fig. 2 is an elevation of the same, and Fig. 3. is a section of the central shaft and cylinder. Fig. 4 is a section of the hoop.

The nature of this invention will be best understood from a description of its construction and mode of operation.

In a suitable frame I place a hollow disk or short cylinder, said cylinder being attached to a hollow shaft or mandrel carrying a pulley, by which the whole machine may be driven. A section of this cylinder, shaft, and pulley is given in Fig. 3, by which it will be seen that it (the cylinder) may be heated by means of steam or hot air, and also that its outer edge is somewhat grooved, so as to guide the hoop splint in its passage around it, and also to allow room for the thick edge of the splints, they being cut somewhat thicker at one edge than the other, as shown in section in Fig. 4. All hoops, moreover, are frusta of cones of greater or less vertical angles, and in forming hoops out of splints in this machine by regu-

lating the pressure of the outer series of rollers, to be presently described, this form can be given to each hoop with the greatest required accuracy. In the same frame which carries the central cylinder, C, I arrange a series of rollers, R R R R R R R, which are adjusted to a proper distance from the cylinder C by means of set-screws, while at the same time entire rigidity is avoided by the use of springs. Motion being communicated to the central cylinder by means of the pulley P, a hoop-splint fed into the machine will pass between the cylinder C and rollers R, and will come out with the proper curve and shape imparted to it.

By means of this machine, lumber, if green, may (after being cut into splints) be formed into hoops without the aid of steaming or boiling. If dry, it will be necessary at least to boil the splints—a much easier process than steaming—when the hot cylinder will squeeze and dry them so as to leave them nearly fit for market, while at the same time their surface is so compressed and smoothed as to add greatly to their appearance and durability.

Having thus described my invention, what I claim therein as new, and desire to secure by Letters Patent, is—

The method herein described of forming splints into hoops by passing them between a series of rollers arranged and operating in the manner and for the purpose substantially as described.

JOHN B. DOUGHERTY.
